UNITED STATES PATENT OFFICE.

KEMPSTER B. MILLER, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

CENTRAL-ENERGY TELEPHONE SYSTEM.

SPECIFICATION forming part of Letters Patent No. 749,798, dated January 19, 1904.

Application filed December 19, 1900. Serial No. 40,372. (No model.)

To all whom it may concern:

Be it known that I, KEMPSTER B. MILLER, a citizen of the United States, residing at Chicago, in the county of Cook and State of Illinois, have invented a certain new and useful Improvement in Central-Energy Telephone Systems, of which the following is a full, clear, concise, and exact description, reference being had to the accompanying drawings, forming a part of this specification.

My invention relates to a central-energy telephone system, my object being to provide an improved form of telephone system wherein the source of current for energizing the talking-circuits and the signaling apparatus is located at the central station.

My invention relates more particularly to the signaling apparatus at the central station by means of which the subscriber signals the operator.

I have shown and described one specific embodiment of my invention for the purpose of illustrating the generic principle underlying my invention. In accordance therewith I provide a relay and a plug-seat switch adapted to conjointly control the signaling device at the central station. I preferably arrange the relay so that the same is energized when the subscribers are connected for conversation, to thereby render the signaling device inert. In this manner the signaling device may be actuated to convey the signal for disconnection to the operator by the hanging up of the subscribers' telephone-receivers. The return of the connecting-plug to its seat serves to actuate the plug-seat switch and again render the signaling device inert.

I have illustrated my invention in the accompanying drawings, in which—

Figure 1 is a diagram showing two subscribers' telephone-lines and the central-station connecting apparatus. Fig. 2 is a detail view of a plug-seat switch. Fig. 3 is a diagram showing the talking-circuit. Fig. 4 is a view of a modified form of the signaling-circuit.

Like characters refer to like parts in the several figures.

The telephone-line A extends in two limbs a' to the central station, where said limbs 50 terminate, respectively, in the springs a² a³, the spring a² normally resting against back contact 1, which is connected to ground, the spring a³ normally resting against back contact 2, which is connected through individual 55 annunciator c to conductor 3. The springs a² and a³ carry armatures resting opposite the poles of the relay-magnet b, and the spring a² when attracted is adapted to engage contact 4, which is connected with the line-springs d' d'. 60 The spring a³ is adapted when attracted to engage contact 5, which is connected with the sleeves d² d³ of the spring-jacks d d. Moving with the spring a², but insulated therefrom, is a spring a⁴, connected to ground 65 through a resistance a⁵ and adapted when the relay is energized to engage contact 6, which is connected with the test-rings d⁵ d⁶. One end of the winding of relay b is connected 70 with conductor 3, and the other end is connected with the contact-springs d³ d³, which springs are mounted to move with but insulated from the line-springs d' d', respectively. When the plug is inserted in the spring-jack, the line-spring d' is moved by the tip thereof 75 to carry the spring d³ into engagement with the grounded contact d⁴.

The subscriber is provided at the substation with the usual microphone f, receiver f', and switch-hook f², normally resting against contact 7, which is connected through bell f³ to ground. When the telephone is removed from the hook, the hook engages contact 8, which is connected with the telephone-transmitter and receiver. The telephone-line B shown at 80 the right of the drawings is like the telephone-line A and is provided with the same parts and mechanism, and like parts have been indicated by the same reference characters employed in connection with the line A.

The answering-plug p is provided with a tip p' and a sleeve p², the tip being connected with a strand t, while the sleeve is connected with a strand s. The calling-plug o is provided with a tip o', connected with strand t', 95 and with a sleeve o², connected with a strand

s' . The strands are inductively united through windings of a repeating-coil w , said repeating-coil comprising windings w' w^2 , connected to the strands t and s , and windings w^3 and w^4 , connected between strands t' and s' . A battery r is interposed between the windings w' and w^2 , and a battery r' is interposed between the windings w^3 and w^4 .

A ringing-key g' normally rests against contact 17 and is adapted when depressed to engage contact 18, which is connected to ground through generator g . The operator's telephone set i is adapted to be bridged between the strands t' and s' , and a condenser l is included in circuit therewith to prevent the passage of the battery-current.

The conductor 3, extending to a portion of the subscribers' lines centering at the exchange, is connected with one pole of the battery r , while the conductor 3, extending to the remaining telephone-lines, is connected with the battery r' . The opposite poles of the batteries r and r' are grounded. The plugs p and o normally rest in plug-seats, and plug-seat switches are provided adapted to be actuated by the insertion of the plugs in their respective seats and by the removal of the same therefrom. The answering-plug p is adapted when inserted in its seat to separate the spring m^2 from contact 14, and likewise the plug o is adapted to separate the spring v^2 from contact 16.

In circuit with the strand s is a relay-magnet h , shunted by a non-inductive resistance k' , and in circuit with the strand s' is a relay-magnet k , shunted by a non-inductive resistance k' . Opposite the magnet h is a contact-spring m , carrying the armature of the magnet and normally engaging contact 13. Opposite the relay k is a similar spring v , normally engaging contact 15. The signaling-lamp m' is included in circuit with the battery r and with the contacts of relay h and of the plug-seat switch actuated by plug p . Likewise the lamp v' is included in circuit with the battery r' and with the contacts of the relay k and of the plug-seat switch belonging to plug o .

I will now describe the manner in which the subscribers are connected together for conversation. Supposing subscriber A desirous of conversing with subscriber B, he lifts his telephone-receiver from its hook, thereby closing together limbs a and a' at the substation and completing the circuit of battery r from ground over conductor 3, individual annunciator c , contact 2, spring a^3 , limb a' , limb a , spring a^2 , contact 1, to ground. The annunciator c is thus actuated, thereby attracting the attention of the operator, who removes the answering-plug p from its seat and inserts the same in the spring-jack belonging to subscriber A. The insertion of the plug in the spring-jack moves spring d^3 against contact d^4 , thereby energizing the relay b , the

circuit through said relay being traced from ground through battery r , conductor 3, relay b , spring d^3 , contact d^4 , to ground. The relay-magnet b upon being energized attracts the armatures carried upon springs a^2 and a^3 70 and separates said springs, respectively, from contacts 1 and 2 and moves the same against contacts 4 and 5. The individual annunciator c is thus removed from circuit, and the terminals of the spring-jacks are connected with the limbs of the telephone-line. The circuit of battery r is now closed through relay h over strands s and t and limbs a and a' , thereby energizing the relay h and causing the same to attract the armature thereof to thus 80 maintain the circuit through lamp m' open. The circuit through the lamp m' , which was closed by the removal of the plug p from its seat, is thus opened, and the lamp is thus extinguished. The operator now bridges her 85 telephone set in circuit and having learned the number of the called subscriber lifts the calling-plug o and touches the tip o' thereof to the test-ring d^5 to determine whether or not the line of subscriber B called for is busy. If 90 subscriber B is busy, his relay b will be energized and spring a^4 thereof will rest against contact 6. Upon touching the tip of the calling-plug to the test-ring the operator will hear a click in her telephone if the line is busy and 95 the relay energized; otherwise her telephone will remain silent. This click is caused by the fact that before the tip is touched to the test-ring the point where the operator's telephone set is connected with the strand t' is of the 100 same potential as the battery r' , since the battery is on open circuit. When, however, the tip is touched to the test-ring, the circuit of battery r' is closed from ground through winding w^3 , strand t' , tip o' , test-ring d^5 , contact 105 6, spring a^4 , to ground, and due to the fact that the winding w^3 is interposed between the pole of the battery and the point where the telephone set is connected with the strand t' the potential at this point of connection will be 110 lowered and a current will thus flow through the receiver of the telephone set which will cause a click therein. If the line of subscriber B is not busy, this circuit above traced will be open between spring a^4 and contact 6, 115 and the operator will thus fail to hear any click and will know that the line is not busy. Thereupon the operator inserts the calling-plug o in the socket belonging to subscriber B and depresses the ringing-key g' , thus sending calling-currents from ground through generator g , strand t' , limb a , through subscriber's bell f^3 , to ground. The bell of subscriber B is thus 120 actuated, and when subscriber B removes his telephone-receiver from the hook, limbs a a' 125 are closed together at the substation. The circuit of battery r' is thus closed through relay k over strands t' s' and limbs a a' of substation B. When the operator removes the calling-plug o from its seat, the circuit through 130

lamp v' is closed and the lamp is lighted. When the called subscriber responds and lifts his telephone from the hook, thus closing the circuit of battery r' through relay k , the spring m is separated from contact 13, thus opening the circuit through lamp v' and extinguishing the same.

The talking-circuit is shown in diagram in Fig. 3. The variation of resistance caused by the operation of the microphone of subscriber A varies the current delivered by battery r , thus causing a vibrating current to traverse the windings w' and w^2 of relay w , thereby inducing corresponding current in the windings w^3 and w^4 , which traverse the receiver of subscriber B. Likewise vibratory currents produced by the microphone of subscriber B are transmitted to the receiver of subscriber A. When the subscribers have completed their conversation, they hang up their telephone-receivers, and the limbs a a' are thus separated at the substation. Thus when subscriber A hangs up his telephone-receiver the limbs a a' are separated at the substation and the circuit of battery r through relay k is opened, thereby deenergizing said relay and permitting spring m to engage contact 13 to thus close circuit through lamp m' and light the same. Similarly the hanging up of the receiver of subscriber B lights the lamp v' . The lamps thus remain lighted until the plugs have been returned to their respective seats. Thus when plug p is returned to its seat spring m^2 is separated from contact 14, thereby opening the circuit through lamp m' and extinguishing the same. Likewise the return of plug o to its seat extinguishes lamp v' . The lamp of the called subscriber is thus lighted as soon as connection is made with his line and is extinguished as soon as he removes his telephone-receiver from the hook, thereby giving the operator the signal that the subscribers are in conversation. The hanging up of the telephone-receiver of either subscriber lights the lamp corresponding thereto to thereby indicate to the operator that disconnection is desired. Either subscriber may by vibrating his switch-hook alternately light and extinguish his lamp to indicate in the usual manner a desire for reconnection.

In Fig. 4 I have illustrated a modification of the signaling-circuit. The relay k instead of being provided with a back contact is provided with a front contact, the spring m and contact 13 being connected with opposite sides of the lamp m' . When the relay is energized, the spring m makes contact with contact 13, thus short-circuiting the lamp and extinguishing the same. In this modification the relay when energized closes together its contacts to extinguish the lamp, while in the form above described the relay when energized separates these contacts to extinguish the lamp. A resistance k^2 prevents the short-circuiting of the battery when the lamp is cut out. This ar-

rangement does away with the necessity of a back-contact relay.

I disclaim herein the matter claimed in the patent to Francis W. Dunbar for telephone-switchboard systems, dated November 12, 1901, No. 686,272.

Having described my invention, what I claim as new, and desire to secure by Letters Patent, is—

1. The combination with a pair of telephone-lines, of a cord-circuit to loop said lines together for conversation and having a connecting-plug at each end, a pair of sources of electricity one for each line of the connected pair, a relay associated with each end of the cord-circuit and operated over the telephone-line during conversation from the corresponding source of current but deenergized when the subscriber's telephone is not in use, a plug-seat switch for each of the connecting-plugs, and a supervisory signal for each end of the cord-circuit controlled by the conjoint action of the relay and plug-seat switch associated with the corresponding end of the cord-circuit, substantially as described.

2. The combination with a plurality of telephone-lines, of a cord-circuit to loop any of said lines together in pairs for conversation and having a connecting-plug at each end, a pair of sources of electricity, one for each line of each connected pair, and placed in circuit therewith by the act of connecting the cord-circuit with the lines, a relay associated with each end of the cord-circuit and operated over the metallic telephone-line from the corresponding source of current, a plug-seat switch for each plug, and a supervisory signal for each end of the cord-circuit controlled by the conjoint action of the relay and plug-seat switch associated with the corresponding end of the cord-circuit, substantially as described.

3. The combination with a plurality of telephone-lines, of a cord-circuit to connect any of said lines together in pairs for conversation and having connecting-plugs, a pair of sources of electricity one for each line of each connected pair and placed in circuit therewith by the act of connecting the cord-circuit with the lines, the ends of said cord-circuit being inductively united together but conductively disconnected, a relay associated with each end of the cord-circuit and operated over the telephone-line from the corresponding source of current, a plug-seat switch for each plug of the cord-circuit, and a supervisory signal for each end of the cord-circuit controlled by the conjoint action of the relay and plug-seat switch associated with the corresponding end of the cord-circuit, said signal being actuated whenever the relay is deenergized and the plug is out of the seat and rendered inoperative whenever the plug is in its seat or the relay energized, substantially as described.

4. The combination with a plurality of telephone-lines, of a cord-circuit to connect any

of said lines together in pairs for conversation and having connecting-plugs, means to conductively separate but to inductively join the ends of said cord-circuit, a pair of sources of electricity, one bridged across each end of the cord-circuit and adapted to be included in the metallic telephone-line when a connection is established, a relay for each end of the cord-circuit and in the path of current over the metallic line, a plug-seat switch for each plug, and a supervisory signal for each plug having its circuit controlled by the corresponding switch and by said relay and so that the signal is actuated when the plug is out of its seat and the relay deenergized and is rendered inoperative at other times, substantially as described.

5. The combination with a plurality of telephone-lines, of a cord-circuit to connect said lines in pairs for conversation, said cord-circuit being provided with connecting-plugs, a repeating-coil interposed between said plugs to inductively unite the same together and to conductively separate them, a separate source of current associated with each end of the cord-circuit and adapted to send current over the metallic telephone-lines when a connection is established, a relay for each end of the cord-circuit in the path of current over the metallic telephone-line, a plug-seat switch for each plug, and a supervisory signal for each plug having its circuit controlled by the corresponding switch and relay, substantially as described.

35. 6. The combination with a plurality of telephone-lines, of a cord-circuit to connect said lines together in pairs for conversation and having connecting-plugs, a repeating-coil having its windings connected across between the strands of said cord-circuit to inductively join the ends of the same together and to conductively separate them, a separate source of current connected with each end of the cord-circuit and between the windings of said repeating-coil, a relay associated with each end of the cord-circuit and in one strand thereof, said relay being in the path of current over the metallic telephone-line, a plug-seat switch associated with each end of the cord-circuit for the connecting-plug, and a supervisory signal for each plug having its local circuit controlled by the corresponding relay and plug-seat switch, substantially as described.

55. 7. The combination with a plurality of telephone-lines, of a cord to variously loop said lines together for conversation and having a connecting-plug at each end, said cord-circuit having only two strands and the ends thereof being conductively discontinuous but inductively united, a pair of sources of electricity associated with the cords and lines, one source being independently included in the circuit of each line during the connection, a separate and independent relay associated with each end of the cord-circuit and included in the

metallic circuit with the corresponding source of current and telephone-line when a connection is established, and a supervisory signal for each end of the cord-circuit controlled during conversation by said relay, substantially as described. 70

8. The combination with a plurality of telephone-lines, of a cord-circuit to connect any of said lines together in pairs for conversation and having a connecting-plug for each end, means to conductively separate but inductively unite the said ends of the cord-circuit, a pair of sources of electricity, one bridged across each end of the cord-circuit and adapted to be included in the metallic circuit with the corresponding telephone-line when a connection is established, a separate and independent relay for each end of the cord-circuit and in the path of current over the said corresponding metallic telephone-line, and a supervisory signal associated with each connecting-plug and controlled during conversation by the corresponding relay, substantially as described. 75 80 85

9. The combination with a plurality of telephone-lines, of a cord-circuit to connect any of said lines together in pairs for conversation and having a connecting-plug for each end, means to conductively separate but inductively unite the said ends of the cord-circuit, a pair of sources of electricity, one bridged across each end of the cord-circuit and adapted to be included in the metallic circuit with the corresponding telephone-line when a connection is established, a separate and independent relay for each end of the cord-circuit and in the path of current over the said corresponding metallic telephone-line, a supervisory signal associated with each of the connecting-plugs, a local circuit for each said signal, said circuits being controlled at one point by the corresponding relays and at another point by auxiliary means, substantially as described. 90 100 105

10. The combination with a plurality of telephone-lines, of a cord-circuit to connect any of said lines together in pairs for conversation and having a connecting-plug for each end, means to conductively separate but inductively unite the said ends of the cord-circuit, a pair of sources of electricity one bridged across each end of the cord-circuit and adapted to be included in the metallic circuit with the corresponding telephone-line when a connection is established, a separate and independent relay for each end of the cord-circuit and in the path of current over the said corresponding metallic telephone-line, a supervisory signal for each end of the cord-circuit, local circuits for said signals, said relays serving when actuated to open said local circuits at one point to render the said signals inert during conversation, and other means to close said circuits when the plugs are connected with the lines so that the said signals may be operated when the subscribers' telephones are 110 115 120 125 130

not in use, and to open the same when the plugs have been disconnected from the lines so that the said signals are again rendered inert, substantially as described.

- 5 11. The combination with a plurality of telephone-lines, of a cord-circuit to connect any of said lines together in pairs for conversation and having a connecting-plug for each end, means to conductively separate but inductively unite the said ends of the cord-circuit, a pair of sources of electricity, one bridged across each end of the cord-circuit and adapted to be included in the metallic circuit with the corresponding telephone-line when a connection is established, a separate and independent relay for each end of the cord-circuit and in the path of current over the said corresponding metallic telephone-line, a supervisory signal

associated with each plug, means controlled by each said relay for depriving the corresponding signal of operating-current when the said relay is energized whereby said signal is rendered inert during conversation, and other means for supplying current to said signals when the connection is established and for depriving them of current when the connecting-plugs have been returned to normal position whereby said signals are normally inert, substantially as described.

In witness whereof I have hereunto subscribed my name in the presence of two witnesses.

KEMPSTER B. MILLER.
